UNITED STATES PATENT OFFICE.

GEORGE A. WARD, OF CHICAGO, ILLINOIS.

INTERMITTENT-VACUUM MASSAGE-MACHINE.

1,378,922.

Specification of Letters Patent. Patented May 24, 1921.

Application filed May 31, 1919. Serial No. 300,827.

To all whom it may concern:

Be it known that I, GEORGE A. WARD, a citizen of the United States, and a resident of the city of Chicago, in the county of Cook 5 and State of Illinois, have invented certain new and useful Improvements in Intermittent-Vacuum Massage-Machines; and I do hereby declare that the following is a full, clear and exact description of the same, 10 reference being had to the accompanying drawings, and to the numerals of reference marked thereon, which form a part of this specification.

This invention relates more particularly 15 to an improved type of a massaging machine wherein a vacuum is intermittently applied by the machine to parts requiring massaging.

It is an object of this invention to provide 20 a massaging machine adapted to produce an intermittent vacuum when operated.

It is also an object of the invention to construct a massaging device adapted to be manually or electrically operated to intermittently 25 produce vacuums in the applicator for massaging purposes.

A further object of the invention is the construction of a massaging machine wherein a gear operated pump is adapted to be actuated to produce intermittent vacuums in 30 the applicator of the machine.

It is furthermore an object of this invention to provide a massaging machine having a pump mechanism adapted to be operated 35 alternately to create and release a vacuum in the applicator of the machine.

It is an important object of this invention to provide a massaging machine of simple and effective construction adapted to permit 40 massaging to be done by intermittently applying and releasing a vacuum at the applicator of the machine.

Other and further important objects of this invention will be apparent from the disclosures in the specification and the accompanying drawings.

The invention (in a preferred form) is illustrated in the drawings and hereinafter more fully described.

50 On the drawings:

Figure 1 is a side elevation of a massaging machine embodying the principles of this invention.

Fig. 2 is a rear view thereof.

55 Fig. 3 is an enlarged longitudinal section of the machine showing parts in elevation.

Fig. 4 is a sectional view taken on line 4—4 of Fig. 3.

Fig. 5 is a transverse section taken on line 5—5 of Fig. 4.

Fig. 6 is an enlarged fragmentary detail section taken on line 6—6 of Fig. 2.

Fig. 7 is a longitudinal section with parts in elevation, of a modified form of massage machine.

Fig. 8 is a sectional detail view taken on line 8—8 of Fig. 7.

Fig. 9 is an elevational view of another modified form of the device.

Fig. 10 is an enlarged detail section taken on line 10—10 of Fig. 9.

Fig. 11 is an enlarged fragmentary bottom plan view of the honey-combed pad applicator shown in Fig. 10.

As shown on the drawings:

The reference numeral 1, indicates a case tapered toward its outer end and having a handle 2, rigidly attached axially on the opposite rounded end thereof. Journaled in one of the side walls of the casing 1, is a 80 stub shaft or pin 3, having a large gear wheel 4, keyed on the inner end thereof within the casing. A crank 5, is secured to the outer end of the shaft 3, to permit rotation of the driving gear 4. Rotatably 85 mounted on a stud or pin 6, is a small gear 7, which is in mesh with the large gear 4. Secured eccentrically in one side of the upper gear 7, is an eccentric pin or screw 8, which projects through a slot 9, formed in 90 a head 10. The head 10, is rigidly secured to the lower end of a plunger rod or stem 11, which projects through the upper end of the casing 1, and projects into a pump cylinder or housing 12, mounted rigidly upon the upper end of the casing. Secured on the upper end of the rod 11, within the cylinder 12, is a piston or plunger 13, suitably packed. The outer end of the pump cylinder 12, is closed by means of a head 14, to which one 100 end of a curved pipe or elbow tube 15, is secured. The outer end of the tube 15, has a rubber cap applicator 16, attached thereto.

As clearly shown in Fig. 6, a valve cup 17, is secured upon the cylinder head 14, and 105 communicates with the interior of the cylinder 12, through a tapered passage. Adjustably threaded into the upper end of the valve cup 17, is a screw 18, the lower end of which is tapered to form a needle valve 19, adapted to fit into the tapered passage to control the entrance or escape of air from the in-

terior of the pump cylinder 12, through an inlet opening or passage 20, provided in one side of the valve cup 17.

In the modified form of the device shown 5 in Figs. 7 and 8, the machine comprises a longitudinally passaged casing or handle 21, through which a rotatable driving rod or shaft 22, axially projects. The outer end of the shaft 22, is threaded and has a nut 10 23, engaged thereon for holding the shaft in position. A dish or plate 24 is secured or integrally formed on the inner end of the shaft 22. Secured on the end of the handle 21, is a casing or housing 25, on one end of 15 which a passaged guide sleeve 26, is secured. Attached to the opposite end of the casing 25, is a pump cylinder 27, within which a piston or plunger 28, is disposed. Connected to the plunger 28, is one end of a rod or 20 stem 29, the other end of which is positioned to slide in the guide sleeve 26. Integrally formed on the stem 29, intermediate the ends thereof, is a head 30, provided with a slot 31. Projecting through the slot 31, 25 and rigidly secured eccentrically to the disk 24, is an eccentric pin or screw 32. The outer open end of the pump cylinder 27, is closed by means of a head 33, to which one end of a pipe or tube 34 is secured. Removably attached to the other end of the 30 tube 34 is a rubber cup applicator 35. This form of massaging machine is adapted to be electrically driven by connecting the threaded end of the shaft 22 with a flexible 35 motor driven shaft.

Figs. 9 to 11, inclusive disclose another modified form of intermittent vacuum massaging machine embracing a pump 36, having one end of an eccentric rod or shaft 37, 40 connected to the outer end of the plunger rod or stem 38, of the pump. The other end of the eccentric rod 37, is eccentrically attached to a disk or plate 39, adapted to be rotated by a worm wheel 40, which is driven 45 by a worm 41, mounted on the shaft 42, of an electric motor 43. Attached to the pump cylinder 36, is one end of a pipe or tube 44, the other end of which is removably attached to a multiple cup or honey-combed pad applicator provided with attaching straps 45.

The multiple cup pad applicator comprises a back 46, made of a flexible or semi-flexible material and having the attaching straps 45, secured to the outer surface thereof, to permit the pad applicator to be conveniently applied and secured in position upon the body of a person to be massaged. Integrally formed on one margin of the applicator back 46, is a sleeve or elbow 47, into 55 which one end of the tube 44, is secured. The back 46, is provided with a marginal groove on the inner surface thereof. Seated in the groove of the back 46, is the peripheral flange 48, of a pad 49, which is made 60 of rubber or any other flexible material. 65

The flange 48, is secured to the margin of the back 46, by washers 50 and retaining members 51. The pad is shaped to afford a chamber 52, between the back and said pad. Integrally formed on the outer surface of the pad 49, are a plurality of hexagonally shaped walls or webs 53, forming a plurality of cells or small applicator cups, the walls of which are common. Each cell is provided with an aperture or opening 54, 70 communicating with the chamber 52. The cup walls or webs 53, are all of the same height, and as shown taper outwardly. 75

The operation is as follows:

In the form of intermittent vacuum massaging machine shown in Figs. 1 to 6, inclusive, the machine is operated manually by turning the crank 5. The rubber cup shaped applicator 16, is applied to the portion of the skin of a person to be massaged, 80 and by rotating the crank 5, the gears 4 and 7, are rotated. Rotation of the gear 7, serves to operate the eccentric mechanism 8-10, whereby the pump plunger 13, is reciprocated in the cylinder 12. On the up stroke 90 of the plunger the air in the cylinder 12, above the plunger 13, is forced outwardly through the tube 15, and out between the applicator 16, and the portion of the skin to which the applicator has been applied. 95 Upon the down stroke of the pump plunger 13, the suction at the mouth of the applicator causes the skin to be drawn into the applicator thereby causing a partial vacuum to be formed in the tube 15 and in the chamber above the plunger 13. During the down stroke of the plunger the air below the plunger is permitted to escape through the opening 47, provided for the purpose. It will thus be seen that a partial vacuum is created 100 and then released or broken with each rotation of the gear 7. The intermittent vacuum produced at the mouth of the applicator 16, acts to massage the skin by alternately sucking and then releasing the skin as the machine is operated. Should the suction created by the vacuum be too strong the needle valve 19, is adjusted by turning the screw 18, thereby permitting a small quantity of 105 air to enter the vacuum chamber during the driving stroke of the pump plunger 13. The degree of pressure reduction may thus be varied by the machine, depending upon the adjustment of the valve mechanism. If preferred the machine may be easily arranged 110 to be power driven.

The modified form of massaging machine disclosed in Figs. 7 and 8, is operated in a manner similar to that already described. In this case the eccentric mechanism is operated by the shaft 22, which is adapted to be rotated by means of a motor or by any other suitable means connected to the threaded outer end of said shaft. The intermittent vacuum effect is produced at the appli- 115 120 125 130

cator 35, as the plunger 28, is reciprocated. The machine is adapted to be conveniently held by the handle 21, during a massaging operation. In the modified form of the alternate vacuum massaging machine shown in Figs. 9, 10 and 11, the pad applicator is secured in place by means of the straps 45. By starting the motor 43, the pump 36, is operated to alternately vary the pressure at the place where the massaging face of the pad is applied to a person being massaged.

The variations in pressure at the cup applicators caused by the action of the pump, serve to thoroughly massage the skin by alternately drawing blood to the parts being massaged and then releasing the pressure. The skin tissues are thus enlivened. The pad applicator is flexible to permit the same to conform to the portion of a body to which it is applied, and the rubber walls forming the plurality of cells or cups, are also adapted to so grip the skin so that communication between the various cells is obviated, thereby permitting a plurality of small skin areas to be massaged simultaneously.

It will of course, be understood that any desired form of applicators may be used other than those shown, and that the intermittent vacuum effect may be produced by operating mechanisms different from the mechanisms described.

I am aware that numerous details of construction may be varied through a wide range without departing from the principles of this invention and I therefore do not purpose limiting the patent granted otherwise than necessitated by the prior art.

I claim as my invention:

1. An intermittent vacuum massaging machine comprising a cylinder, an imperforate piston adapted to reciprocate in said cylinder, a piston rod connected to the piston, a head integral with the piston rod having a longitudinal slot substantially per-

pendicular to the axis thereof, a circular driving plate, a stud eccentrically mounted on the driving plate and adapted to engage the slot in the head, means for rotating the driving plate thereby actuating the piston rod and piston, a massaging applicator and a tube connecting the interior of said applicator with the cylinder whereby said applicator is directly operated by the variations of pressure produced by the reciprocation of the piston.

2. The combination with a device adapted to rapidly produce and release a pressure, of a pad applicator connected therewith and having a chamber therein, and a plurality of cells formed on the applicator and each provided with an opening communicating with said chamber.

3. A massaging applicator comprising a back, an elbow formed thereon, a pad attached to said back to afford a chamber between the back and pad, and a plurality of walls integral with the pad forming a plurality of separated cells, each of said cells provided with an opening communicating with said chamber.

4. A massaging applicator comprising a flexible back, an elbow formed thereon, means attached to said back affording a means for securing the applicator in position, a flexible pad secured to said back and separated therefrom to afford a chamber between said back and pad, and walls integrally formed on the pad forming a plurality of hexagonal cells, each provided with an opening communicating with said chamber.

In testimony whereof I have hereunto subscribed my name in the presence of two subscribing witnesses:

GEORGE A. WARD.
